UNITED STATES PATENT OFFICE.

FRED L. MCGAHAN, OF INDIANAPOLIS, INDIANA.

WATER-GAGE.

SPECIFICATION forming part of Letters Patent No. 394,870, dated December 18, 1888.

Application filed August 15, 1888. Serial No. 282,784. (No model.)

To all whom it may concern:

Be it known that I, FRED L. MCGAHAN, a citizen of the United States, residing at Indianapolis, in the county of Marion and State 5 of Indiana, have invented a new and useful Improvement in Water-Gages, of which the following is a specification.

My invention relates to an improvement in that class of water-gages for steam-boilers in 10 which a glass tube is mounted outside the boiler and connected at both ends with the interior of the boiler.

The objects of my improvement are to permit the removal of the glass tube without disturbing the boiler-connections, to permit the 15 use of glass tubes of different lengths, and to provide improved means for holding the adjustable parts in position.

The accompanying drawings illustrate my 20 invention.

Figure 1 represents a side elevation. Fig. 2 represents a central longitudinal section. Fig. 3 represents a transverse section at *a*, Fig. 1.

25 A and B are hollow castings constituting tubular quarter-turn fittings adapted to be screwed into the shell of the boiler, one above and the other below the water-line, arranged with their opposed open ends turned toward 30 each other. Each of said fittings is provided with a suitable stop-cock, as at *b* and *c*, whereby communication with the interior of the boiler may be cut off. The open outer 35 end of fitting B is adapted to receive and support one end of the glass tube C, and is screw-threaded on the outside and provided with the usual stuffing-box, D, through which the glass tube passes.

40 The outer open end of fitting A is screw-threaded, and is provided with a sliding coupling consisting of the stuffing-box E and a short metallic tube, F, adapted to slide longitudinally in stuffing-box E. Tube F is adapted at its outer end to receive and support 45 one end of the glass tube C, and is provided with a stuffing-box, G, through which the glass tube passes.

For the purpose of cleaning out fittings A and B they are each provided at the bend 50 with a removable plug, *p*.

H is a bracket, which is adjustably secured on the fitting A, preferably by threading it, so

as to fit the threaded portion *i* of the fitting. The lower part of bracket H terminates in a split bearing, J, through which tube F slides, 55 said bearing being adapted to clamp the tube by means of a screw, *k*, and to thus hold the tube in a fixed relation to the fitting A.

The upper part of bracket H is perforated to receive the upper ends of the guard-rods 60 *g*, the lower ends of which rest in a suitable support on the lower fitting, B.

In operation, the glass tube C having been cut to a suitable length, tube F is pushed as far as possible into its supporting-fitting A. 65 Fittings A and B are now screwed into the boiler-front, one above and the other below the water-line, at such a distance apart that the ends of tube C will pass easily between them. Tube C, carrying the stuffing-boxes 70 G and D, is now inserted in the open end of fitting B, and the open end of tube F is then drawn down over the other end of tube C, and is then clamped rigidly in position, so as to prevent any strong pressure on the ends 75 of the glass tube by tightening screw *k*, and thus closing bearing J. The stuffing-boxes are now packed and screwed in place and a tight tubular connection is formed between the fittings A and B. Heretofore, when it 80 has been necessary to remove the glass tube for cleaning or other purposes, it has been necessary to carefully turn the connections A and B from each other, which operation is quite liable to break the glass and to cause a leak 85 at the point where the connections enter the boiler. These difficulties are overcome by the use of my device, it only being necessary to release clamp J and slide tube F inward to release the glass, and if a short piece should 90 be broken off from the glass tube it may still be used by drawing tube F farther outward.

I claim as my invention—

In a water-gage, the combination of fittings A and B, glass tube C, sliding tube F, having 95 one end adapted to receive the end of the glass tube, stuffing-box E, bracket H, and the clamp J, all arranged to co-operate substantially as specified.

FRED L. MCGAHAN.
